UNITED STATES PATENT OFFICE.

JOHN K. CUMMINGS, OF ST. LOUIS, MISSOURI.

DESIGN FOR A BOTTLE OR FLASK.

SPECIFICATION forming part of Design No. 14,925, dated April 1, 1884.

Application filed February 1, 1884. Term of patent 7 years.

To all whom it may concern:

Be it known that I, JOHN K. CUMMINGS, of the city of St. Louis, in the State of Missouri, have invented and produced a Design for 5 Flasks or Bottles, of which the following is a full, clear, and exact description, reference being had to the accompanying drawings, forming part of this specification.

Figure 1 is one half in elevation and one 10 half in section at line 1 1, Fig. 2. Fig. 2 is a horizontal section at 2 2, Fig. 1.

The peculiarities of this bottle or flask are, first, a flat portion, A, at each side, said portions being parallel with each other; second, 15 the shoulders C are in the arc of a circle having a radius equal to one-half the width of the bottle or flask; third, the edges A' of the bottle or flask are vertical and semicircular in horizontal section, the radius of the semicircle 20 being equal to one-half the thickness of the

bottle or flask; fourth, on the bottom of the bottle or flask is a foot, D, and between the foot and the vertical parts A' are round portions I, the bottom of the bottle being, like the top, semicircular, except where foot D cuts 20 the same. The body of the bottle or flask has no sharp curves or corners.

It will be understood that the bottle or flask is what is known as "flat," and that its edges, top, and bottom are formed with true semi-circular curves, except where the neck and foot interfere.

I claim as my invention—

The design for a bottle or flask, having the shape or configuration shown and described.

JOHN K. CUMMINGS.

In presence of—

SAML. KNIGHT,
GEO. H. KNIGHT.
